UNITED STATES PATENT OFFICE.

FRIEDRICH EILHAUER, OF NEUSTADT, GERMANY.

POWER WEAVING LOOM.

Application filed December 1, 1923, Serial No. 678,063, and in Germany December 1, 1923.

The invention relates to power looms, and its particular object is a new method of and means for boxing and picking the shuttles, whereby the violence of the impact of 5 the shuttle is checked and a smooth running of the loom attained, together with other advantages.

According to the invention, the box which receives the shuttle at the end of its stroke 10 is also used as a means for driving the shuttle, that is to say as picker, under the action of a picker stick, and for this purpose it is mounted to be adjustable horizontally on the lay in such a manner as to take up the 15 oncoming shuttle gradually, and after being struck by the picker stick, discharge the shuttle afresh.

According to the invention, moreover, the shuttle and the picker stick and picker are 20 provided with means for coupling them together at the time of impact, and for uncoupling them when the shuttle is being discharged in the picking stroke. The member guided on the lay in longitudinal direction 25 is further connected with a device for pulling and tightening the weft thread or twist after the impact and coupling of the shuttle. This device is formed by the picker stick with which the coupling element, for 30 instance the picker is connected by an intermediate member of adjustable length, with the result that the travel of the shuttle can be adapted to the width of the fabric.

An embodiment of the invention is illustrated by way of example, in the accompanying drawings in which the picker serving at the same time as shuttle box is provided with means for coupling it with the shuttle and for pulling the shuttle and the 40 weft after the impact of the shuttle on the picker.

Fig. 1 is a front elevation, some parts being broken away, showing the lay of a loom with the driving mechanism for the picker.

Fig. 2 shows in plan view one end of the shuttle path with the shuttle and the picker.

Fig. 3 shows in side elevation part of the loom with the lay and the mechanism for operating the lay and the picker, partly in section.

Figs. 4 and 5 show another embodiment of a device for operating the picker, partly broken away, and in front elevation and side elevation respectively.

In these figures 1 represents the shuttle race of the lay, which is mounted on the lay sword 3 secured on the rocking shaft 2. A member 4, serving as picker and also as shuttle box, is adapted to slide longitudinally on the race and is articulated by means of an intermediate member 5, the length of which is adjustable, to a picker stick 7 subjected to the tension of a spring 6. The picker stick 7 is connected to the lay in known manner so that it can rock in the plane of the rocking shaft 2 and lay swords 3. The picker stick 7 is articulated to a crank 9, by means of a connecting rod 8, said crank being mounted on a shaft 10 supported on the lay. The shaft 10 also carries 70 a ratchet wheel 11, with a notch 12, on which slides a spring pawl 14 articulated on a chain roller 13 mounted idly on the shaft 10. The chain roller 13 is connected, on the one hand, with a continuously driven crank 16 by means of an attached chain 15, with an intermediate member, and on the other hand with an opposing return spring 17. By means of the chain or rope drive 15, the ratchet and pawl mechanism 12, 11 the crank 9, connecting rod 8, picker stick 7 and link 5, the crank 16 effects the return stroke of the shuttle box and picker mechanism 4, until the dead point of the crank 16 and crank 9 is passed, the crank 9 being held fast, 80 against the action of the spring 6, by a locking member 18 pivotally mounted on the lay whilst the chain roller 13 is rotated in the reverse direction by the return spring 17. The locking member 18 is displaced, during 85 the return stroke of the lay, by a chain 19, so that the picker stick 7 swings, under the action of the spring 6 and propels the picker 4 forward.

When the lay oscillates around shaft 2 to the left (Fig. 3) a chain 19 securely holds the locking hook 18 so that its top end is pulled off from under the crank arm 9.

A two-armed pawl 21, influenced by a spring 20, is pivoted on the picker 4 at the 100

point 22, and at the moment of impact of the shuttle 24 against the picker 4, the nose 23 of said pawl, under the action of the spring 20, engages in a notch 25 on the shuttle. At the point at which the forward movement of the picker ends, the race 1 is provided with a stop 26, against which the rear arm 27 of the coupling pawl 21 strikes during the advance of the picker, whereby the nose 23 is lifted out of the notch 25 of the shuttle. In the example shown, the stop 26 is formed as a pivotal pawl which remains stationary in its position at the moment of the picking stroke, and gives way during the return stroke of the picker. The recess in the rear arm 27 of the pawl is for the purpose of enabling the return of pawl 21 into the receiving position after the picking of the uncoupled shuttle. The abutment 26 is however prevented by a stop pin from oscillating in opposite direction. The stop 26 is adapted to oscillate in outward direction so that the coupling pawl can be pulled back. The front end of the picker 4 is provided with a projection 28, the sloping contact surface of which is adapted to the shape of the shuttle nose, said surface taking up the pressure of the coupling pawl 21 which tends to tilt the shuttle.

At the moment of impact of the shuttle 24 against the picker 4, the latter has preferably commenced its return stroke already and has moved a certain distance from the stop 26. The nose of the shuttle runs up the sloping surface of the projection 28 on the picker, and the pawl 23 drops into the notch 25 in the shuttle 24, which is hereby coupled to the picker 4. The movement of the shuttle merges into the picker movement set up by the picker stick 7. After the impact of the shuttle, the weft thread is tightened by the return stroke of the picker, until the crank 9, after passing the dead point, is caused to bear against the stop 18 by the pull of the spring. Drawing back the stop 18 releases the spring 6, whereby the picker stick 7 is thrown forward along with the picker 4. On the pawl arm 27 coming in contact with the fixed stop 26, the nose 23 is lifted out of the notch in the shuttle 24, and when the picker 4 goes to rest, the released shuttle continues its stroke alone.

The described mechanism for operating the picker stick 7 and picker 4 may be replaced by the usual form of striker-motion (Figs. 5 and 6) consisting of an underpick picker stick 43, swung by an eccentric or roller arm 44 and acting on a short arm 41 of the picker stick 42. In this case the return stroke of the picker stick 42 with which is connected the picker 4, is effected by means of a tappet 46, mounted on the eccentric shaft 45 and controlling a roller arm 47 connected to the under pick picker stick 43.

For different widths of fabric, the shuttle

box and picker can be adjusted by shortening or, lengthening the connecting rocker arms 5, thus adapting the stroke of the shuttle to the width of the fabric.

I claim:—

1. In a loom of the fly motion type the combination of a shuttle propelled across the loom free from engagement with any propelling means, mechanisms on the picker for catching the shuttle, of mechanisms on the picker and shuttle for coupling the shuttle with said picker at the impact of the shuttle against said picker, and of mechanisms on the lay for uncoupling said shuttle from said picker at the throwing of said shuttle. 70

2. In a loom of the fly motion type as claimed in claim 1 the combination of mechanisms for withdrawing the picker after it has been coupled with the shuttle. 80

3. In a loom of the fly motion type as claimed in claim 1, the combination of a coupling pawl on the picker, a notch in the shuttle designed to receive said coupling pawl, a fixed abutment on the lay arranged in the path of the shuttle so that at the forward movement of the picker said coupling pawl is disengaged from the notch of the shuttle. 85

4. In a loom of the fly motion type as claimed in claim 1, the arrangement on the picker of a projection turned towards the shuttle and having a guide surface in conformity with the pointed shape of the shuttle. 95

5. In a loom of the fly motion type as claimed in claim 1, the combination of mechanisms for the pulling back of the picker after its coupling with the shuttle, these mechanisms consisting of a picker stick hingedly connected with the picker, means for slowly pulling back the picker, and means for rapidly throwing the picker forward. 100

6. In a loom of the fly motion type as claimed in claim 1, the combination of mechanisms for the pulling back of the picker after its coupling with the shuttle, these mechanisms consisting of a picker stick hingedly connected with the picker, means for slowly pulling back the picker, consisting of a spring, a crank hingedly connected with said picker, and means for rapidly throwing the picker forward, a locking mechanism executing an oscillating movement corresponding to half a rotation of said crank, means for locking said crank after passing through the dead point position, and means for releasing the locking to effect the throwing of the shuttle. 115

7. In a loom of the fly motion type as claimed in claim 1, the combination of mechanisms for the pulling back of the picker after its coupling with the shuttle, these mechanisms consisting of a picker stick hingedly connected with the picker, means 120

130

140

150

160

170

180

190

200

for slowly pulling back the picker and means
for rapidly throwing the picker forward,
these means consisting of a system of levers
connected with an arm of the picker stick
5 and two lifting devices of which the one
controls the throwing motion and the other
the return motion of the arm of the picker
stick.

8. In a loom of the fly motion type as
claimed in claim 1, means of adjustable ¹⁰
length for hingedly connecting said picker
with said picker stick.

Signed at Leipzig this 13th day of November
1923.

FRIEDRICH EILHAUER.
